BOTTLE FOR MALT LIQUOR

Edward J. Goodall, 3944 Suitland Road SE,
Washington, D.C.

Filed Dec. 22, 1961, Ser. No. 68,024

Term of patent 14 years

(Cl. D58—6)

It is to be understood that the ornamentation is continued over the entire surface of the article as indicated by the broken lines. The sides and bottom not shown are substantially like the sides and top shown.

I claim:

The ornamental design for a bottle for malt liquor, as shown and described.
